US00D579019S

(12) **United States Design Patent**
Lei et al.

(10) **Patent No.:** US D579,019 S
(45) **Date of Patent:** ** Oct. 21, 2008

(54) **CHIP**

(75) Inventors: **Leo Lei**, Guangzhou (CN); **Raymond Wang**, Guangzhou (CN)

(73) Assignee: **Podium Photonics (Guangzhou) Ltd.**, Guangzhou, Guangdong Province (CN)

(**) Term: **14 Years**

(21) Appl. No.: **29/304,270**

(22) Filed: **Feb. 27, 2008**

(30) **Foreign Application Priority Data**

Aug. 27, 2007 (CN) 2007 3 0153939

(51) **LOC (8) Cl.** 14-02

(52) **U.S. Cl.** D14/435; D14/437; D13/180

(58) **Field of Classification Search** D14/435-438; D13/180, 182, 162; 257/79, 744, 10, 414, 257/415, 368, 690, 749, 461, 13, 21, 63, 257/19, 88, 200, 201, 212, 187, 288, 918, 257/776; 435/6; 445/50; 427/569; 428/408, 428/367; 204/450; 313/495, 311, 309; 324/464, 324/207.2; 338/195, 20; 524/233; 315/502; 361/751; 977/742, 938

See application file for complete search history.

(57) **CLAIM**

The ornamental design for a chip, as shown and described.

DESCRIPTION

FIG. 1 is a perspective view of a new chip design;

FIG. 2 is a front elevational view thereof;

FIG. 3 is a top plan view thereof;

FIG. 4 is a rear elevational view thereof;

FIG. 5 is a left side elevation view thereof;

FIG. 6 is a right side elevation view thereof; and,

FIG. 7 is a bottom plan view thereof.

1 Claim, 3 Drawing Sheets

Fig.1.

*Fig.2.**Fig.3.**Fig.4.**Fig. 5.**Fig. 6.**Fig. 7.*
